UNITED STATES PATENT OFFICE

110,187

DESIGN FOR A SHIRT DISPLAY STAND

Max C. Meyer, Brooklyn, N. Y.

Application February 4, 1938, Serial No. 74,856

Term of patent 3½ years

To all whom it may concern:

Be it known that I, Max C. Meyer, a citizen of the United States, residing at Brooklyn, in the county of Kings and State of New York, have invented a new, original, and ornamental Design for a Shirt Display Stand, of which the following is a specification, reference being had to the accompanying drawing, form part thereof.

I claim:
The ornamental design for a shirt display stand, as shown.

MAX C. MEYER.
